UNITED STATES PATENT OFFICE.

JOHN H. HARTMAN, OF LANCASTER, PENNSYLVANIA, ASSIGNOR TO THE HUBLEY MANUFACTURING CO., OF LANCASTER, PENNSYLVANIA, A CORPORATION OF PENNSYLVANIA.

DESIGN FOR A TOY CIRCUS WAGON.

Application filed December 9, 1922. Serial No. 4,542. Term of patent 3½ years.

To all whom it may concern:

Be it known that I, JOHN H. HARTMAN, a citizen of the United States, residing at Lancaster, in the county of Lancaster and State of Pennsylvania, have invented and produced a new, original, and ornamental Design for a Toy Circus Wagon, of which the following is a specification, reference being had to the accompanying drawings, forming a part thereof.

The figure is a perspective view of a toy circus wagon, illustrating my new design.

I claim:

The ornamental design for a toy circus wagon, as shown.

In testimony whereof I have signed my name in the presence of two subscribing witnesses.

JOHN H. HARTMAN.

Witnesses:

JOSEPH M. BRENEMAN,
JOHN KUMMER.
